UNITED STATES PATENT OFFICE.

GEORGE E. PALMER, OF CHICAGO, ILLINOIS, ASSIGNOR TO THE BABCOCK & WILCOX COMPANY, OF NEW YORK, N. Y.

STEAM-BOILER FURNACE.

SPECIFICATION forming part of Letters Patent No. 251,791, dated January 3, 1882.

Application filed August 12, 1881. (No model.)

To all whom it may concern:

Be it known that I, GEORGE E. PALMER, of Chicago, in the county of Cook and State of Illinois, have invented certain new and useful improvements relating to Steam-Boiler Furnaces; and I do hereby declare that the following is a full and exact description thereof.

I employ an inclined grate to promote a traverse of the fuel from the upper to the lower portion of the grate as required. The fuel is supplied through a hopper extending across the whole upper side of the grate. It becomes heated by its contiguity to the furnace, and so soon as it touches and begins to receive air through the grate its gas ignites and burns; but the supply of air at this stage of its progress is too little for complete combustion.

I propose to use in this furnace mainly those varieties of coal which, when heated, give off large volumes of volatile combustible matter—in other words, to use the bituminous or blazing coal. In the treatment of the upper portion of the inclined grate only partial combustion is attained; but a large proportion of the volatile material is given off and rises, mingled with carbonic oxide, both gases capable of further and intense combustion under proper conditions. If these gases are allowed in this condition to strike the cooler surfaces of the boiler, they part with their heat and escape unconsumed into the atmosphere, producing visible and offensive smoke. I defend the cool surfaces of the boiler against the contact of the gases in this condition. The furnace has what I term a "deep hanging bridge," of fire-brick or analogous material, capable of enduring a high temperature, which divides its upper portion into two compartments or chambers. In the first the combustible gases are liberated and mixed with air and the whole at a high temperature brought to such condition that, on its passage under the hanging bridge and receiving additional air, complete combustion, with the production of intense heat, ensues. The air supplied to this volume of combustible gas in the second chamber of the furnace is itself at a high temperature. What takes place there is really the combination of a hot mixture in which there is an ex-

cess of the combustible gas with a hot mixture in which there is an excess of air.

I have demonstrated by experiment that the construction and mode of operation shown result in a complete combustion of all that is combustible in the fuel with little labor or skill. A marked gain results from the invention. I present what I believe to be the correct theory, but I do not rest the claim on the correctness of the theory.

The accompanying drawings form a part of this specification, and represent what I consider the best means of carrying out the invention.

Figure 1 is a central longitudinal section through the entire furnace and boiler. Fig. 2 is a central longitudinal section through the main portion of the furnace on a larger scale. Fig. 3 is a front view of the same, partly in section.

Similar letters of reference indicate corresponding parts in all the figures.

My boiler is of the style known as "Babcock & Wilcox."

A, &c., are the barrels, horizontal cylinders, of twenty (20) or more inches in diameter, of which there may be a number side by side, but only one is shown; B, a series of inclined tubes, say, four (4) inches in diameter; C and D, connections which allow a constant circulation from the barrels A down through D, forward through B, and up through C.

E is a mud-drum, extending across under the rear and connected at a sufficient number of points.

G is a horizontal transverse tube of, say, six (6) inches in diameter. It is connected by pipes $g' g^2$ with the other portions of the boiler. The pipe g' leads from the back connection, D, and brings water into one end of the pipe G. The pipe g^2 leads upward from the other end of G, and conveys into the barrel a current of water liberally mingled with steam, which is generated during the passage through the pipe G.

I employ an inclined grate, having horizontal grate-bars assembled in two systems, each system having horizontal bars, arranged in groups, which alternate with the bars of the

other series—that is to say, there are five stationary bars, I, at the top of the incline, then a considerable interval, and five more stationary bars, similarly marked, at a lower point, then 5 an interval, and five more, and so on. These bars are bolted to or otherwise supported on the fixed work at the sides, and are never moved except in repairing or exchanging. Another 10 system, J, is in similar divided sets, having a corresponding number of horizontal bars connected together on a sufficient framing, J', with freedom to be moved considerably forward and back.

K' K' are levers or movable arms, extending 15 upward from sleeves K and engaging with J'. These levers are free to rock or oscillate on sufficient fixed shafts or round bars k. The lowermost sleeve, K, has a socket which receives a hand-lever, L. By moving the lever L up and 20 down, either constantly or at intervals, the entire series of levers K' K' is rocked and the alternate sections of grate J are moved forward and backward between the fixed sections I.

25 W W' is a crank shaft, rotated slowly by a belt or gearing from the engine. (Not represented.)

30 X is a loop of small chain, leading from the crank W', and taking hold of the hand-lever L. When this chain is thus engaged it will automatically rock the grate. The point of connection of the chain X with the lever L may be shifted inward and outward, and thereby the extent of the motion varied. When it 35 is shifted outward to its farthest extent the movement is only sufficient to take up the lost motion in the connections, and there is no actual shaking of the grate. When it is shifted inward but little the grate is shaken slightly 40 by the moderate rotation of the crank. Under many conditions the attendant may after a few trials find a point in which this chain may be so adjusted that the fuel will be slowly worked down in the grate automatically as required.

45 M is the front side of a sufficiently capacious hopper, into which the fuel is introduced, either constantly or at intervals. The back face of the hopper is an inclined hollow casing, O, of cast-iron or other suitable material, through 50 which atmospheric air is distributed into the furnace through apertures o. The air is admitted to the case O, at one or both sides of the furnace, through an adjustable register, N.

55 P is a horizontal grate, extending from the inclined grate I J to the bridge-wall or back masonry, F, which bounds the fire space. This grate P is mounted sufficiently below the fire-grate, as indicated, to allow of slicing between.

A considerable part of the front side of the 60 grate P is covered by a dead-plate, P'. Ordinary provisions (not shown) allow this grate P to be shaken or dropped when necessary.

The pipe G forms the lower edge of a hanging bridge, which is composed of fire-brick or 65 other suitable refractory material, R, and extends up to the lowermost of the inclined tubes

B. The spaces between these lowermost tubes, B, from the top of this bridge R forward, are closed by fire-bricks or other suitable non-conducting material, R', forming a nearly horizontal tight platform. This platform or floor 70 ing R', which I term the "lower" platform, and the nearly vertical bridge R, with the stout water-tube G at the base of the latter, perform the important function of separating 75 the front portion of the fire-chamber from the rear portion thereof and from the space between the tubes above. They compel the gases rising from the upper and main portion of the inclined grate I J to descend and pass close 80 to the surface of the more advanced and thoroughly-coked fuel on the lower portion of the inclined grate I J and on the horizontal grate P. Care must be taken to rock the lever L sufficiently to move the fuel down, but not so 85 much as to move it too fast and cause it to accumulate too thickly at the bottom. A sufficient space must be left for the gases generated in the front chamber, x, to pass under the pipe G, and consequently under the entire 90 hanging bridge G R, into the rear chamber, y. At this point they meet and mingle with a current of hot gases, composed largely of atmospheric air which has passed up through the coke and cinder resting on the horizontal grate 95 P in the base of the furnace. The combustible elements in the solid portions are completely burned by receiving a large excess of fresh air on the grate P. The hot gas rising from the fuel on P has much free oxygen. The 100 two opposite grades of gas mingle and complete the combustion of the volatile elements in the chamber y in rear of the pipe G. The combustion is unusually intense. The flame is bright and short. It will now be seen that all 105 the volatile elements of the fuel are utilized by disengaging them in the front chamber, x, and sending them downward and rearward at a high temperature, mingled with not nearly air enough for the combustion, and then presenting them in the chamber y to a current of highly-heated but relatively fresh air at a high temperature, which has been inducted through the thoroughly utilized solid fuel at the bottom. It is easy to so conduct this operation that the 110 combustion will be complete, nothing being left on the grate P but earthy matter, and nothing going up the chimney but completely-burned gases. The hot gases resulting from the complete combustion in the chamber y 115 move upward through the zigzag spaces between the tubes B, and are, by the cross-partition T and a nearly horizontal connected platform, T', compelled to traverse forward. They move upward past the front edge of what 120 I term the "upper" platform, T', then rearward, bathing the barrels A, then downward between the cross-partition T and another cross-partition, U, imparting more of their heat to the tubes B, and, after moving rearward in 125 the space under the latter, they rise and again 130 traverse through the zigzag spaces between

the tubes B and are discharged into a stack. (Not represented.)

The provisions for utilizing the heat developed are closely analogous to those in the ordinary Babcock & Wilcox boiler. My invention pertains mainly to the means for insuring a uniform and complete combustion of the fuel and generating the heat. Complete combustion is effected in a furnace requiring only 10 moderate space and easy of manipulation.

P' is a dead-plate extending forward from the front edge of the horizontal grate. It serves to accumulate a sufficient quantity of cinders and ashes, or of fuel in a half-burned condition, 15 and to hold such matter there in a relatively cool state. This enables me to allow a considerable space between the lower edge of the inclined grate and the top of the grate P without realizing such a heat there as to melt the 20 iron or do any other mischief.

L' is a portable weight, provided with a hook or other convenient means of attachment, which may be removed whenever it is desired to shake the lever L, and consequently the frame J' and 25 bars J by hand. The chain X being removed, either by slipping its loop off the end of the hand-lever L or by disconnecting a hook or other simple attachment from the lever L or from the crank W', or from both, the lever L 30 may be vibrated up and down as vigorously as the exigency requires. Under more favorable conditions, the chain X being connected to the crank W' at the top and to such point in in the hand-lever as shall be found to give such 35 sufficient reciprocation to the lever, a moderate motion may be maintained constantly. The lever L may be notched on the under side to hold the chain against shifting its position, and also, if desired, on the upper side to hold the 40 weight L' in position.

Modifications may be made in the forms and proportions within wide limits. I can adjust the angle of the fresh-air casing O by the employment of chipping-pieces at the surfaces of 45 contact, which can be chipped off, filed, or otherwise changed as experience with a given kind of fuel shall dictate. I can work with some success without the casing O. I can introduce a greater or less number of bars in each of the 50 horizontal sections I and J. I can, if desired, have every alternate bar stationary and every intermediate bar movable; but I prefer the arrangement shown with alternate sets or groups of five, or about that number, movable, and a 55 corresponding, or nearly corresponding, number stationary.

Bituminous fuels vary greatly, not only in their chemical constituents, but in their mechanical conditions in burning. Large lumps 60 of fuel may require a removable cover on the hopper M to prevent air from entering the furnace through the large interstices.

The throw of the crank W' may be varied by shifting the crank-pin in a radial slot, or otherwise so as to vary the extent of motion of 65 the chain X.

In place of the chain X, I can substitute a rigid link, with a hook or other ordinary means of engaging with the lever L. I can substitute another lever to serve in this relation independent of the hand-lever L. I esteem it important that the automatic motion be capable of easy adjustment, and also of being thrown out of use entirely to allow the grate to be shaken by hand when desired. 70

I attach much importance to the fact that the hanging bridge R and the lower platform or furnace-roof, R', are not water-surfaces, but fire-brick or analogous material adapted to assume and maintain a high temperature, so that 80 the gases will be first mixed with air in limited proportions, and distilled into combustible gas and burned into carbonic oxide at so high temperature that all the matter will be thoroughly combined, and then that the gases thus produced will, after passing under the hanging bridge, be exposed to and mingled with the hot gases rising from the lower portion of the furnace containing an excess of air under such conditions that all the particles will be also 85 there combined, producing carbonic acid. I incase the water-tube G in suitably-formed fire-bricks, to prevent it from direct exposure to the hot gases, and thus avoid the refrigerating effect which it would otherwise produce. 90

My furnace, having the properly-formed chambers *x* *y* thus bounded by surfaces which may be raised to a very high temperature, is very different from any, however closely approaching it in form, in which the surfaces are naked 100 portions of a boiler filled with water, and consequently maintained at a relatively low temperature. It is important that the chambers be so proportioned as to allow a proper space with no great surplus of space for the two operations—that is to say, the production of hot combustible gas in the first chamber, *x*, and the burning it completely under the conditions prescribed in the second chamber, *y*. The proportions may require to be varied with different kinds of fuel and different conditions with regard to draft. My experiments indicate the proportions shown are about right for using soft coal from the Illinois bed burned with natural draft. 110

I can use the other parts of the invention successfully, with the substitution of an ordinary stationary grate inclined the same as here shown, or a little more nearly horizontal, and supplied with fuel by shoveling through a door 120 instead of distributing through a hopper. My most successful experiments with this furnace have thus far been made with such stationary grate. 115

Parts of the apparatus may be used without 125 the whole; but I prefer to employ the whole, combined and arranged about as shown. Where a number of the furnaces are employed side by side one shaft, W, may extend across the front of the whole, with a crank, W', introduced at the front of each furnace. I do not here claim the grate or the arrangements 130

for working it. Such will form the subject of a separate application for patent.

I claim as my invention—

1. The hanging bridge R and lower plat-
5 form, R', in combination with the back mas-
sonry, F, partition T, and upper platform, T',
and with the boiler A, inclined tubes B, and
connections C and D, as herein specified.

2. The case O, having provisions for receiv-
10 ing and distributing air arranged at the front
of the furnace and receiving air in adjustable
quantities from the side or sides, in combina-
tion with a hopper and with a hanging bridge
and an inclined grate, as herein specified.

15 3. In a furnace formed in two partially-sepa-
rated chambers, the first lined with non-con-
ducting material on all sides and above, and
the second similarly lined on all sides, an in-
clined grate with provisions for feeding fuel
20 slowly down thereon, a hanging bridge, and a
transverse tube, G, having connections g' g² to
a steam-boiler, A, combined and arranged to
serve as herein specified.

4. The method herein set forth of obtaining
the complete combustion of partly solid and 25
partly volatile fuel by first distilling off the
volatile matter and partially burning the solid
matter in a chamber inclosed within non-con-
ducting walls, then discharging both the gase-
ous and the remaining solid matter at an ex- 30
traordinary temperature into a second chamber,
also inclosed, or nearly so, within non-conduct-
ing walls, in which second chamber the solid
matter is completely burned with an excess of
air and the gases therefrom mingled with the 35
gaseous matter from the first chamber, all sub-
stantially as herein specified.

In testimony whereof I have hereunto set my
hand, this 8th day of July, 1881, in the presence
of two subscribing witnesses.

GEO. E. PALMER.
